SHIRTS WITH ATTACHED COLLARS

Jean René Lacoste, Paris, France

Application January 20, 1958, Serial No. 710,091

Claims priority, application France July 19, 1957

4 Claims. (Cl. 2—116)

This invention relates to shirts provided with attached collars such as sports shirts which have become widely used since they are comfortable to wear, hitherto the comfortable character of the shirt has been incompatible with the correctness essential for a formal shirt which could be worn for everyday use and at work.

The present invention has as its object to provide a shirt which fulfills both these requirements; comfort and correctness, at the same time. The invention provides a shirt neck and collar which enable a neat correct closure to be obtained without using a button or stud, the shirt can also be worn equally well with or without a tie.

It is known that shirts or like garments exist which comprise, in prolongation of the neck opening and on the front of the garment, a triangular yoke constituted by a knitted or woven fabric which allowed a certain elasticity in the transverse sense, without the use of buttons or studs. A neck thus formed allows the shirt to be slipped over the head easily, and allows complete freedom of movement to the user's neck, and the use of buttons or studs thus dispensed with.

In certain cases, shirt necks of this type are augmented by collars of various types, but the addition of the collar entails reduction in the dimensions of the triangular insert in order to avoid too great a distance between the ends of the collar, or alternatively to fix the collar to the top of the triangular insert, which is used base up, and thus annul the elasticity of the triangular insert. In all cases, it is difficult to wear a tie, and after a few movements of the neck, even fairly gentle movements, there is a risk that the collar will move upwards or downwards relatively to the position of the tie, which is generally not very elastic and therefore relatively fixed in position. The result is often, more particularly, an unattractive lack of balance in the apparent length of the two outer points of the collar.

In the shirt according to the invention the shirt neck comprises at the front a triangular cutaway part which may be wider than in prior known similar shirts, so as to permit the easy passage of the user's head, and is fitted with a yoke in the form of a triangle base up, which is elastic in the transverse sense and is connected by stitching to the edges of the cutaway part of the shirt; the neck is completed by a collar, preferably formed of a band folded over on itself in the sense of its length and which when fixed in position on the one hand allows the triangular yoke to retain all its elasticity and on the other hand permits the two ends of the collar to be brought together at the front, which gives the appearance of a "formal" collar and facilitates wearing a tie. This fixing of the collar to the shirt neck is, under normal conditions, effected at the rear of the neck and at the sides down to the two points at which the fastening of the elastic yoke to the edges of the triangular cutaway commences. From these two points, the folded band or collar which is made to straddle each of the lateral points of the elastic yoke is fixed by the edge of

2

its inner portion—and over a certain length—to the edges of the triangular cutaway of the shirt neck; under these conditions, the horizontal upper edge of the triangular yoke i.e. the upwardly directed base is absolutely free, which allows the triangular yoke to retain all its elasticity.

According to alternative forms of embodiment, the outer part of the band which constitutes the collar may be either entirely free or fixed, by sewing, to the top 10 of the shirt neck all round or only at the sides and at the front between the top of the shoulder and the points at which the shirt neck cutaway part is fixed to the yoke, or as far as the end of the points of the collar. Even in this case the triangular yoke remains free and completely elastic within and between the faces of the collar.

The attachment of the outer part of the collar to the shirt neck may advantageously be effected in such manner that the two sides of the collar which at the front are situated astride the lateral points of the triangular 20 yoke, are mounted slightly above the upper edge of the said yoke. In fact, a position slightly above may be desirable in order to permit the triangular yoke to remain quite flat on the front of the chest (without breaking at the base of the wearer's neck) and at the same time 25 to permit a normal and correct position of the tie with a slightly higher collar to be obtained.

With such an arrangement the visible part of the triangular yoke is reduced to a surface which can be given, for example, a square or diamond shape and the sides 30 of the collar are brought to the neck by the inherent elasticity of the collar in cases where the said collar is itself made of a mesh fabric which allows such elasticity in the requisite direction, that is to say, about the neck.

Individually or together, the features aforesaid prevent 35 gaping and deformation of the shirt neck in cases where the shirt is worn without a tie and furthermore allow a tie to be worn with a collar made of elastic fabric.

Finally, in view of the form of the cutaway, the inner 40 portion of the band constituting the collar could, at the sides and rear, be taken below the shirt fabric so as to reduce the height of the collar at the rear and at the sides relatively to its height at the front. Other methods of reducing the height of the collar could also be used, for example by cutting away the collar in an appropriate manner.

Shirts embodying the improvements according to the invention can easily be pulled on, they are pleasantly comfortable to wear, and they give the shirt a correctness of appearance comparable with that of a formal shirt.

The following description with reference to the accompanying drawings, which are given by way of non-limitative example, will make it readily understood how the invention can be carried into effect, the features 55 which are brought out both from the drawings and from the text being understood to form part of the said invention.

Figure 1 is a perspective view showing a normal shirt neck.

Figure 2 is a similar view showing the cut of the shirt in the region of the collar, according to the invention.

Figure 3 is a perspective view of a shirt neck with elastic yoke augmented by a collar constructed according to the invention.

Figures 4, 5 and 6 are sectional views on a larger scale, taken on the lines IV—IV, V—V and VI—VI of Figure 3 respectively.

Figures 7 and 8 are detail views.

Figures 9 and 10 are diagrammatic views of two alternative forms of embodiment.

In ordinary shirts (Figure 1) the shirt neck 1 or called

band has a substantially circular periphery corresponding to the size of the user's neck, with some clearance allowed to permit free movements of the wearer's neck inside.

According to the invention, the shirt A comprises a neck 2 whose rear portion a, o, b (Figure 2) is similar to the corresponding portion of the normal neck or collar band 1. On the other hand the front part of the neck is so cut, in the general form of a triangle, a, c, b, as to constitute a large cutaway part with a view to permitting the easy passage of the shirt over the user's head; the cutaway part a, b, c is larger, as will be seen from Figure 2, than that already formed in certain shirts of known construction (indicated at d, e, f), the lateral edges of the cutaway a, c, b being connected directly to the rear portion a, o, b. As in the case of the said prior known shirts, a triangular yoke 5 as indicated at g, h, i (Figures 3 and 8) and preferably made of knitted or woven fabric, elastic in the transverse sense, is mounted and fixed in the shirt neck cutaway part a, c, b.

The neck, is augmented by a collar 3 (Figures 3 and 7), constructed, in the normal form of shirt collars, either by two bands 3a-3b of the same contour assembled together at their upper edge 3c, or by a single band folded over on its central longitudinal axis 3c, as indicated in section in Figures 4 and 5.

The collar 3 and yoke piece 5 are connected to the shirt A in the following manner.

The inner band 3b of the collar is sewn to the rear part 2a of the shirt neck in the usual way as shown in section in Figure 4, where there is shown the stitching 4 which connects the two elements 2a and 3b, the stitching extending along the line a, o, b.

Then the lateral edges g, h and h, i of the yoke 5 are connected to the corresponding edges of the cutaway 2 and attached thereto by stitching 7 (Figure 6).

The two front ends of the collar, not yet fixed to the shirt neck, are then made to bear against the said neck by arranging the two bands 3a, 3b of the collar astride the lateral corner parts of the yoke 5 and the two bands 3a, 3b are then sewn together as at g, g' and i, i' (Figure 3) along the edge of the cutaway 2, along which edge the yoke 5 has already been sewn, as indicated hereinbefore; Figure 5 shows this mode of stitching.

5 is the yoke, 2 is the edge of the cutaway and, on either side, the bands 3a and 3b of the collar the whole being connected by stitching 8.

According to a modified form of embodiment as illustrated diagrammatically in Figure 9, the ends of the outer band 3a of the collar are free, the stitching of the inner band 3b extending along the line g', g, a, o, b, i, i' whilst the stitching of the outer band would only be effected along the line g, a, o, b, i,

With an alternative method of assembling the parts, the stitching 4 is taken along the rear part of the collar between the points g and i corresponding to the tops of the yoke, and then a single stitching would be effected about the periphery g, c, i, as indicated at 9 in Figure 3.

Whatever the form of embodiment, the upper horizontal edge g, i of the yoke is free, that is to say it does

not have any stitching, thus allowing the yoke 5 to retain all its extensibility.

In these conditions, the transverse elasticity of the yoke can be used freely to permit the head to pass through the shirt neck and then to bring the edges of the neck into their normal position.

The collar, owing to the fact that the two bands 3a and 3b thereof are connected to the edge of the shirt neck and the edges of the yoke 5, is always correctly held in position when the shirt is worn.

10 According to a modified form of embodiment as illustrated in Figure 10, the top of the triangular yoke, i.e. the line g, i forming the base has been slightly spaced by the distance k from the top of the collar, so as to avoid crumpling the triangular yoke and to permit a higher collar position when wearing a tie.

15 Further bearing in mind the form of the cutaway, the inner portion of the band constituting the collar could come down, at the sides and rear, under the fabric of the shirt so as to reduce the height of the collar at the rear and at the sides relatively to its height at the front, at the points. It would also be possible to reduce the height of the collar, for example by shaping the band appropriately.

20 It will be apparent that modifications may be made to the forms of embodiment which have just been described, more particularly by the substitution of equivalent manufacturing presses, without departing from the scope of the present invention as defined by the appended claims.

25 30 What I claim and desire to secure by Letters Patent is:

1. A shirt with an attached collar having a neck encircling portion provided with a triangular cutaway part formed apex down at the front of said shirt, a triangular shaped yoke of transversely elastic material sewn base up to the edges of said cutaway part along two adjacent sides respectively, and a collar comprising an inner band and an outer band said inner band being sewn to the edge of the shirt neck encircling portion and to at least a portion of the edges of said cutaway part, whereby the front ends of said collar may be held close to one another without hindering the extensibility of said yoke.

2. A shirt as claimed in claim 1 wherein said yoke is made out of knitted fabric.

3. A shirt as claimed in claim 1 wherein the outer band of said collar is sewn to the edges of said neck encircling portion and of said cutaway part, at least along a portion adjacent to the ends of said outer band.

4. A shirt as claimed in claim 1, wherein the height of said triangular shaped yoke and the height of the front part of said collar are such that the top of said collar is spaced from the base edge of said yoke.
